UNITED STATES PATENT OFFICE.

CHARLES A. LINDEN, OF JAMESTOWN, NEW YORK, ASSIGNOR TO THE CORRY METAL FURNITURE COMPANY, OF CORRY, PENNSYLVANIA.

SHEET-METAL BEDSTEAD.

984,823.

Specification of Letters Patent. Patented Feb. 21, 1911.

Application filed December 12, 1910. Serial No. 596,779.

To all whom it may concern:

Be it known that I, CHARLES A. LINDEN, a citizen of the United States, residing at Jamestown, in the county of Chautauqua and State of New York, have invented new and useful Improvements in Sheet-Metal Bedsteads, of which the following, taken in connection with the accompanying drawings, is a specification.

10 The invention relates to metallic furniture and particularly to sheet metal bedsteads, as shown in Letters Patent No. 899,173, of Sept. 22, 1908; and the objects of my improvement construction are, first, to provide a hollow 15 side rail construction which greatly strengthens and stiffens said side rails; second, to provide means for rigidly attaching the side rails to the tubular bed posts which greatly strengthens and stiffens the bed frame; and 20 third, to provide a strong bed slat having novel means of attachment to the side rail which prevents the movement of the bed slat along the side rail and strengthens the supporting ends of the bed slat; and the invention 25 consists in the construction and arrangement of the parts shown in this description and the accompanying drawings and pointed out in the claims.

In the drawings, Figure 1 is a perspective 30 view of a side rail attached to a bed post and a portion of a bed slat attached to said side rail. Fig. 2 is a perspective view of one end of the bed slat attached to the side rail, the side rail being shown in section; and Fig. 3 is a side elevation of the end of the bed slat 35 detached from the side rail. Fig. 4 is a side elevation of the side rail showing the hooks at each end. Fig. 5 is an end elevation of the side rail; and Fig. 6 is a side elevation of the end of the side rail. Fig. 7 is a perspective view of a portion of the bed 40 post showing the slots for the reception of the engaging hooks in the end of the side rail.

45 Similar numerals refer to corresponding parts in the several views.

The numeral 10 indicates the corner bed post. It is preferably formed in a rectangular tubular shape of sheet metal though it 50 may be made in any other form so long as it is made tubular.

The tubular side rail 11 is made with an inturned upper edge 12 having the downwardly projecting lengthwise flange 13 thereon with the inturned lengthwise flange

on the lower edge of lengthwise flange 13, in-turned flange 14 being given an upward angle.

The lower edge of side rail 11 is turned inwardly and upward, as shown at 15 and 60 the lengthwise top of this inturned portion is turned inwardly in the flange 16 which forms a lengthwise box-shaped projection within the rail with an angular edge 17. The edge 18 of the inturned portion 16 is 65 given a lengthwise returned bend toward corner 17.

An L-shaped connective strip 19 is provided having its upper edge 20 turned in the lengthwise downwardly turned flange to engage lengthwise flange 14, and the lower edge 21 of strip 19 is given a reverse lengthwise turn to slidably engage the flange 18 so that lengthwise connective strip 19 may be slipped endwise upon flanges 14 and 18, 75 thereby completing the tubular form and strongly bracing and holding the entire sheet metal side rail.

The side rail 11 is attached to the tubular bed post 10 by means of the L-shaped heavy 80 metal plate 22 which fits within each end of the side rail 11 and is riveted firmly thereto thereby bracing and holding both ends of the side rail in its tubular form. The plate 22 is made L-shaped in order to strongly brace 85 the inner sides of the box-shaped edge 15 and corner 17 of the side rail. The three hooks 23, 24 and 25 are provided on plate 22, the hooking ends of the parts 23, 24 and 25 extending downward and just sufficiently beyond the end of plate 22 and side rail 11 to provide notch 37 which binds closely on the sheet metal cornerpost 10 in correspondingly spaced slots 26, 27 and 28 so as to bind the 90 end of the side rail firmly against tubular post 10 within said slots.

The hooks 23, 24 and 25 are formed on the vertical portions of the L-shaped plate 22 so that the edges of the metal of said hooks rest upon the edge of the metal adjacent the 100 lower sides of slots 26, 27 and 28. Hook 25 with slot 28 is placed to one side of and thereby bracing against the hooks 23 and 24 in slots 26 and 27, thereby greatly strengthening and bracing the hold of the 105 end of the rail 11 upon the tubular post 10 and at the same time rendering it more rigid.

The bed slat 29 is preferably given a tubular form by turning in the lower edges 30 which stiffens and strengthens the entire 110

slat. The ends of bed slat 29 are attached to side rail 11 in the following manner: The sides of the bed slat 29 at each end are cut away as shown at 31 and an angular projecting portion 32 is left within the cut 31. The spaced slots 33 are provided in corner 17 of side rail 11 at spaced intervals to receive the two downwardly projecting edges 32 within cut 31 so that the edges of the cut 10 31 brace against the sides of the box-shaped portion 15 of side rail 11, and the angular projection 32 extends within slot 33 at each side of the slat 29 thereby causing the weight upon slat 29 to rest upon the vertical edges 15 of slot 33 within the slot 33. The sides of the corner slots 33 bracing the sides of the portion 32 of the bed slat and holding both sides firmly in line, thereby using the strength of each of the pieces of metal as 20 they bear endwise upon one another. It is apparent that such a placing of the bed slat upon the side rail permits of the bed slat 25 upholding a great weight, and at the same time strongly braces the bed slat and side rail connection.

The strip 19 is formed in L-shape with the corner bend 34 to stiffen and strengthen said strip 19 and also to provide a horizontal draw upon the flanged edges 18 30 and 21. A space 35 is provided between strip 19 and portion 16 to receive therein the downwardly turned end 36 of bed slat 29 so that the end 36 binds against the joint formed by the edges 18 and 21 and at the 35 same time braces the bedstead and prevents the spreading of the side rails, holding the angular portions 31 and 32 of the bed slat firmly against the side of the part 15 and within the slot 33, thereby stiffening and 40 strengthening the whole construction.

It is obvious that it is difficult in sheet metal construction to obtain rigidity of construction where so many joints or connections are necessary as in the sheet metal, and 45 it is apparent that the herein described improvements strengthen and render rigid those connections which are most liable to

become loose or insecure in bedstead construction.

I claim as new:

1. In a sheet metal bedstead, a side rail having inturned upper and lower edges, oppositely turned flanges on said inturned edges, a connecting strip having oppositely turned flanges to slidably engage said flanges of said inturned edges and form a tubular side rail, and means for attaching bed slats to said tubular side rail. 50

2. In a sheet metal bedstead, a tubular bed slat, the sides of the ends of said tubular bed slats cut away and a projecting part having spaced slots to receive said projection in said cutaway sides of the slat end. 60

3. In a sheet metal bedstead, a tubular side rail composed of two L-shaped pieces 65 having oppositely turned flanged edges to slip one piece onto the other, L-shaped plates riveted in the ends of the larger piece, vertical hooks on said L-shaped plates, and tubular corner posts having vertical slots 70 therein to receive said vertical hooks to support said side rail on said posts. 75

4. In a sheet metal bedstead, a side rail having upper and lower inturned edges, a flange on the upper inturned edge, the lower inturned edge having an upward and inward turn to form a hollow side lengthwise of said rail along the lower side, a lengthwise flange on said lower inturned edge turned oppositely to the flange of said upper inturned edge, a connecting strip having oppositely turned flanges to slidably engage the flanges on said inturned edges, said hollow side on said lower inturned edge having spaced slots to receive the end of the bed 80 slats. 85

In testimony whereof I have signed my name to this specification in the presence of two subscribing witnesses.

CHARLES A. LINDEN.
